PUMPING T PROTECTOR

Ray W. Moorman, Oklahoma City, Okla.

Application October 11, 1940, Serial No. 360,763

6 Claims. (Cl. 308—4)

This invention relates to protectors and more particularly to protectors for pumping T's that are normally arranged on the head of tubing, in an oil well, for example, that is pumped by sucker rods; the principal objects of the invention being to provide a convenient, economical and efficient protector for such pumping T's.

Other objects of the invention are to protect threads in pumping T's, for example, from the abrasion of sucker rods, for example, incident to movement of the sucker rods through the T's; to prolong the life of pumping T's by means of the present protector; to so arrange the protector as to form a support for sucker rod elevators while the elevators are supporting the sucker rods in tubing below the T and while joints are applied to or removed from a sucker rod string; to so arrange the protector as to provide for moving any object therethrough that can be used inside a pipe proportionate in size to the pumping T protector; to provide for efficiently latching the protector to a pumping T in such a manner that special tools are not necessary in the installation thereof; to provide against slipping or change in position of the pumping T protector relative to the tubing head; to facilitate straight and efficient setting of sucker rod elevators relative to sucker rods passing through the protector; to effectively combine an outer clamp and an inner guide relative to a pumping T; and to provide improved elements and arrangements thereof in a pumping T protector of the character and for the purposes noted.

In accomplishing these and other objects of the present invention, I have provided improved details of structure, the preferred form of which is illustrated in the accompanying drawings wherein:

Fig. 1 is a perspective view of a pumping T protector embodying the present invention in applied condition relative to a pumping T.

Fig. 2 is a side elevational view of a well head with my improved pumping T protector applied thereto, sucker rod elevators being shown in dotted lines applied to a sucker rod and supported by the protector.

Fig. 3 is a detail vertical transverse section through a well head and my improved pumping T protector, particularly illustrating the relation of the elements thereof to each other.

Fig. 4 is a plan view of my pumping T protector, the same being shown in closed operative condition.

Fig. 5 is a detail perspective view of the well head and pumping T protector shown in Figs. 1

5 to 4 inclusive, the inner guide of the protector being shown applied to the pumping T and the outer clamping member being shown in disassembled spaced relation to the inner guide.

Fig. 6 is a detail perspective view of my improved pumping T protector, the parts thereof being shown in spaced disassembled inoperative relation.

Referring more in detail to the drawings:

1 designates the head of a well, for example an oil or gas well, that is provided with tubing 2 through which fluids may be pumped from the well. The pumping T 3 is mounted on the upper extremity of the tubing, preferably by the provision of mating threads 4 and 5 on the outer and inner surfaces of the tubing and T respectively and at the lower flanged end 6 of the T. A laterally flanged preferably internally threaded branch 7 of the T is usually provided with a fitting 8 for drawing off fluids that are removed from the well by a pump, not shown, normally arranged in the tubing at the lower extremity of a string of sucker rods 9 that passes through the pumping T.

The upper end of the pumping T is usually internally threaded, as at 10, and, when the sucker rods 9 are applied to or removed from the tubing 2 through the pumping T 3, an abrading action on the threads 10 is encountered which ordinarily renders the threads and the T inoperative for any desired purpose. In overcoming this difficulty, the upper end 11 of the pumping T is preferably provided with an annular groove 12 that cooperates with the upper annular edge 13 of the T in forming an annular flange 14 at the upper end of the T.

An inner guide member, generally designated 15, Fig. 6, is employed for, among other things, covering the pumping T threads 10; this covering protective function being accomplished by the provision of substantially duplicate semi-cylindrical sections 16 and 17 that preferably consist of mating half shells having skirt portions of a length sufficient to cover the threads. The skirt portions of the inner guide member depend from the exteriorly annularly flanged approximately mid-portions of the guide half sections, such flange portions being designated 18 and 19 respectively. The flanges are preferably of a width or thickness sufficient to form shoulders 20 on their lower faces that seat upon the upper edge of the flanged end 14 of the pumping T to support the inner guide in covering relation to the threads of the T. A composite annular groove 21 is provided in the inner guide half sections

immediately above the upper face of the flanges 18 and 19. Above the annular groove 21, the inner guide half sections preferably flare outwardly as at 22 and 23 to form a guiding receptacle or socket for facilitating application of sucker rods to the interior of the guide member that is formed when the guide member half sections are brought together, as shown in Figs. 1, 4 and 5. The guide member half sections are preferably hinged relative to each other as by providing spaced ears 24 and 25 on one of the half sections and an ear 26 on the other half section which latter ear is capable of arrangement between the spaced ears, the ears 24 to 26 having aligned apertures. A suitable fastening device 27 is passed through the apertures for hinging the inner guide forming half sections relative to each other.

The flared ends 22 and 23 of the inner guide forming half sections form a seat for elevators, generally designated 28 and shown in dotted lines in Fig. 2, the elevators seating on the guide member in such a manner that the elevators, when arranged as shown, are always straight and in suitable condition for engaging a sucker rod coupling element 29 whereby sucker rods may be removed from or applied to the tubing through the pumping T.

With the construction thus far described, it is apparent that a guide member has been provided that is capable of directing sucker rods and the like through tubing or pipe while at the same time protecting threads on a connection at the upper end of the tubing or pipe. In order to secure the guide member and thread protector to the pumping T in such a manner that it will serve its intended purpose until such time as it is desired to remove the same from the T, a clamping device 30 is provided, the preferred details of which are clearly shown in Fig. 6.

The clamping device 30 preferably includes a pair of half ring sections 31 and 32. The respective sections are each preferably provided with an internal groove 33 and 34 which, when the sections are brought together, form an annular recess of a height sufficient to receive the flange 14 of the pumping T and the combined flanges 18, 19 on the inner guide member 15. The flanges 35 and 36 formed by the grooves at the lower ends of the ring sections seat in the annular groove 12 in the pumping T and the flanges 37 and 38 at the upper inner ends of the ring sections seat in the groove 21 on the outer face of the inner guide member above the guide member flanges 18, 19.

In order to facilitate application of and removal of the clamping device 30 relative to the inner guide member and pumping T, one of the clamping device ring sections is provided with spaced aligned ears 39 and 40, and the other ring section is provided with an ear 41 that is engageable between ears 39 and 40, the ears 39 to 41 being provided with alignable apertures in which a suitable fastening device 42 is positioned for pivotally connecting the ring sections and providing for their being brought together in surrounding relation to the inner guide member and pumping T.

It is also desirable to positively fix the clamping device in inner guide and pumping T connecting relation and to this end the section 31 of the clamping device is provided with a laterally extending boss 43 adjacent one end thereof which boss is provided with a recess 44 in the outer face 45 thereof. The ring section 32 is

provided with a corresponding boss 46 in which a vertically arranged opening is provided for passing a fastening device 47 that is arranged in aligned openings of arms 48 and 49 of a latch 50. With this construction, the latch 50 is pivotally mounted on the boss 46 of the ring section 32 and when the ring sections are pivoted into adjacent relation, the head 51 of the latch passes over the outer face 45 of the boss 43 in such a manner as to latch the ring sections in closed clamping condition. A set screw 52 is preferably provided in the head 51 of the latch, the inner end of the set screw being engageable in the recess 44 of the boss 43 in such a manner as to positively lock the ring sections in clamping condition.

The inner guide member 15 and the outer clamping member 30 may be and preferably are interconnected in such a manner as to maintain the unitary character of the protector as a whole. This interconnection is preferably accomplished by a provision of a chain 53 or the like, one end of which may be mounted as at 54 on the ear 26 of the inner guide half section 17 and the other end of which chain may be mounted as at 55 on the ear 41 of the ring section 32.

The operation of the pumping T protector constructed as described is as follows:

Assuming a well to be provided with a head, tubing, a pumping T on the tubing and sucker rods for actuating a pump to remove fluids from the well through the lateral outlet 7-8 of the pumping T, the pumping T protector embodying this invention is applied to the pumping T prior to application of the sucker rods to the tubing.

This is accomplished by hinging the inner guide half sections from the open inoperative condition shown in Fig. 6 to the closed operative condition shown in Figs. 1 to 5 inclusive. The closed inner guide member may be manually applied to the upper internally threaded end of the pumping T, the depending skirts of the guide covering the threads of the pumping T and protecting the same. The shoulders on the bottom faces of the flanges of the guide form a seat for the guide on the pumping T and the flared outer ends of the guide sections facilitate application of sucker rods to the T as well as form a support for the sucker rod elevators.

The clamping device 30 is then adjusted from the condition shown in Fig. 6 to the closed operative condition as shown in Fig. 4 about the pumping T and the inner guide and protector therefor, the lower flanges of the ring sections of the clamping device seating in the groove 12 of the pumping T and the upper flanges thereof seating in the groove 21 of the inner guide member; or, in other words, the flange 14 of the T and the flanges 18-19 of the guide are received in the groove 33-34 of the clamping member.

The latch 50 is then pivoted from the condition shown in Figs. 5 and 6 to the condition shown in Figs. 1 and 4 to overlie the boss 43 on the ring section 31, whereupon the set screw is run down into the recess 44 of the boss 43 to positively fix the clamping device relative to the pumping T and inner guide member.

The sucker rods may then be applied to or removed from the well tubing through the pumping T, damage to the pumping T and threads therein meanwhile being obviated.

Due to the relative thinness of the depending skirt portions of the inner guide member pumps, fishing tools and other objects intended to be

operated or acted upon within the tubing may be applied to or removed from the tubing with ease and without the necessity of removing the pumping T protector.

It is apparent, therefore, that I have provided a convenient, economical and efficient pumping T protector that is admirably suited for carrying out the objects for which it is intended.

What I claim and desire to secure by Letters Patent is:

1. A protector for a threaded pumping T comprising a guide member engageable with the T in supported thread covering relation thereto, a clamping member engageable with the T and guide member in supported connecting relation thereto, and flexible means connecting said guide and clamping members together in and out of supported relation to the pumping T.

2. A protector of the character described including an inner guide member comprising hinged sections arranged to completely cover threads at one end of a threaded pumping T, an outer clamping member comprising hinged sections engageable about the T and guide member respectively for interconnecting the same, and means for selectively holding said guide and clamping member sections in closed hinged condition collectively.

3. In a device of the character described, the combination of a pumping T having a flange and a groove arranged exteriorly thereof and threads arranged interiorly thereof, a guide member having a skirt at the lower portion thereof engageable over said threads in covering relation thereto and having a flange seating on a portion of said pumping T for supporting the guide relative to the pumping T, and a clamping device having a flange engageable in the groove of the pumping T and having a groove for receiving the flanges of the pumping T and guide for interconnecting the same.

4. In a device of the character described, the combination of a pumping T having threads, a guide member comprising hinged sections hav-

ing a skirt portion extending over said threads and adapted to be spaced therefrom in covering relation thereto, said guide member having a shoulder for seating on a portion of said pumping T for supporting the guide relative to the pumping T, a clamping device engageable with the pumping T and guide for interconnecting the same, said clamping device holding said guide member in closed condition and the skirt spaced from the threads, and a latch for positively interconnecting said clamping device with said guide member and pumping T.

5. In a device of the character described, the combination of a pumping T having threads, a guide member having a skirt engageable over said threads in covering relation thereto and seating on a portion of said pumping T for supporting the guide relative to the pumping T, a clamping device engageable with the pumping T and guide for interconnecting the same, a latch for positively interconnecting said clamping device with said guide member and pumping T, and flexible means interconnecting said guide member and clamping device.

6. In a device of the character described, the combination of a pumping T having a flange and a groove arranged exteriorly thereof and threads arranged interiorly thereof, a guide member comprising hinged sections having skirt portions extending over said threads and adapted to be spaced therefrom in covering relation thereto and having a flange seating on a portion of said pumping T for supporting the guide relative to the pumping T, a clamping device having a flange engageable in the groove of the pumping T and having a groove for receiving the flanges of the pumping T and guide for interconnecting the same, said clamping device holding said guide member in closed condition and the skirt portion spaced from the threads, and flexible means connecting the guide and clamping members together in and out of supported relation to the pumping T.

RAY W. MOORMAN.
